CAMERA CARRYING CASE OR SIMILAR ARTICLE

Richard R. Wareham, Marblehead, Mass., assignor to Polaroid Corporation

Filed Sept. 26, 1974, Ser. No. 509,796

Term of patent 14 years

Int. Cl. D3—02

U.S. Cl. D87—5 E

FIG. 1

FIG. 4

FIG. 5

FIG. 6

FIG. 1 is a front perspective view of a camera carrying case or similar article showing my new design, shown in an erected condition;

FIG. 2 is a top plan view thereof, shown in a folded condition;

FIG. 3 is a left side elevational view thereof, shown in a folded condition;

FIG. 4 is a bottom plan view thereof, shown in a folded condition;

FIG. 5 is a front elevational view thereof, shown in a folded condition; and

FIG. 6 is a rear elevational view thereof, shown in a folded condition.

Portions of the carrying strap of FIGS. 2-4 have been omitted for ease of illustration.

I claim:

The ornamental design for a camera carrying case or similar article, substantially as shown and described.
